UNITED STATES PATENT OFFICE.

JASON PASSMORE, OF DUNCANNON, PENNSYLVANIA.

WIRE-STRETCHER.

No. 834,534.

Specification of Letters Patent.

Patented Oct. 30, 1906.

Application filed June 28, 1905. Serial No. 267,369.

To all whom it may concern:

Be it known that I, JASON PASSMORE, a citizen of the United States, residing at Duncannon, in the county of Perry and State of Pennsylvania, have invented a new and useful Improvement in Wire-Stretchers, of which the following is a specification.

This invention relates generally to wire-stretchers, the object being to provide a simple and efficient device which can be quickly and easily connected to the wire to be stretched and the stretching operation easily accomplished by hand-power.

A still further object is to provide a stretching device in which the stretching-bar can be quickly and easily disengaged whenever the stretching operation has been accomplished and the wire fastened.

With these and certain other objects in view, as will appear hereinafter, my invention consists in the novel features of construction, combination, and arrangement, all of which will be fully described hereinafter and pointed out in the claims.

In the drawings forming a part of this specification, Figure 1 is a plan view of a wire-stretcher constructed in accordance with my invention. Fig. 2 is a detail view of the bar-holding mechanism. Fig. 3 is a face view of the pawl for holding the bar. Fig. 4 is an edge view of the same.

In carrying out my invention I employ a metal frame A, preferably made of wrought metal and comprising the member A', which practically constitutes the backbone of the frame, and projecting from each end of this member A' are the arms A², the ends of which are enlarged, as shown at A³, and provided with guide-openings through which passes the bar B. A central arm C also projects from the member A', substantially parallel with the arms A², and this arm is also enlarged at its end and provided with a guide-opening through which the bar B passes. This arm, besides constituting a guide-arm, also serves as a bearing for the holding-pawl, as more fully explained hereinafter.

The bar B has a wire-clamp D connected to its forward end, which clamp may be of any suitable construction and is adapted to clamp the wire E to be stretched. A gripping-pawl F works upon the bar B between the arms A² and C and is adapted to grip the said bar and move it rearwardly whenever said pawl is given a rearward movement, and for the purpose of obtaining this rearward

movement I employ a lever G, pivoted at G' to the member A' and connected to the end of the gripping-pawl by means of a link H, which fits over the notched end of the lever. A spring I surrounds the bar B between the bearing-arm C and the gripping-pawl and serves to return said pawl to its forward position as soon as the pull upon the lever is released, thereby enabling the gripping-pawl to obtain a fresh grip upon the bar B.

A holding-pawl K is arranged upon the bar B between the middle arm C and rearward arm A², and a spring L surrounds the bar and bears upon the said holding-pawl. An angled finger M is pivoted to the end of the pawl K and is adapted to bear against the middle arm C for the purpose of holding the pawl K in a proper position for gripping the arm B and holding it against reverse movement while the gripping-pawl is obtaining a fresh grip upon said bar.

N indicates a chain connected to the frame and by means of which the said frame can be anchored or connected to the post or other rigid object, so that by working the lever back and forth the bar B will be moved step-by-step in a rearward direction, thereby stretching the wire E.

After the wire has been stretched and fastened and it is desired to release the bar it can be quickly and easily accomplished by throwing the angled finger M out of engagement with the middle arm, and the holding-pawl will then release its grip upon the bar, and the bar can be moved back to its initial position.

It will thus be seen that I provide an exceedingly strong, simple, and efficient construction of the wire-stretcher.

Having thus fully described my invention, what I claim as new, and desire to secure by Letters Patent, is—

1. A wire-stretcher comprising a frame provided with guide and bearing arms, a bar working through said arms, a gripping-pawl arranged upon the bar, a spring surrounding said bar between said pawl and bearing-arms, a holding-pawl arranged upon said bar, provided with a pivoted finger, a spring surrounding said bar between said holding-pawl and guide-arm and a lever pivoted to the frame connected to the gripping-pawl, for the purpose described.

2. A wire-stretcher comprising a frame consisting of a member having guide and

bearing arms projecting therefrom, a bar working through said arms, a gripping-pawl arranged upon the bar, a lever pivoted to the frame and connected with the gripping-
5 pawl and a holding-pawl arranged upon the bar and carrying a pivoted finger for throwing it into and out of engagement with the bar, as set forth.

3. A wire-stretcher comprising a bar and
10 a frame having a back member and guiding and bearing arms projecting therefrom, a gripping-pawl arranged upon the bar and a

spring bearing thereon, a lever pivoted to the back member of the frame and connected with the gripping-pawl, a holding-pawl arranged upon the bar and having a spring bearing thereon, and an angled finger pivotally connected to the holding-pawl and adapted to bear against the bearing-arms, for the purpose specified. 15
